UNITED STATES PATENT OFFICE.

PAUL MAKRAY, OF CHICAGO, ILLINOIS.

DESIGN FOR A RADIOCABINET.

Application filed March 12, 1926. Serial No. 16,895. Term of patent 7 years.

To all whom it may concern:

Be it known that I, PAUL MAKRAY, a citizen of the United States, and a resident of the city of Chicago, county of Cook, and State of Illinois, have invented a new, original, and ornamental Design for a Radiocabinet, of which the following is a specification, reference being had to the accompanying drawing, forming a part thereof, in which—

Figure 1 is a perspective view, showing my new design as it appears when the cabinet is closed; and

Figure 2 is a similar view, but showing my new design as it appears when the cabinet is open.

I claim:

The ornamental design for a radiocabinet, as shown.

PAUL MAKRAY.
